UNITED STATES PATENT OFFICE.

JOSEPH J. RANNEY AND RALPH D. TINKHAM, OF MONMOUTH, ILLINOIS.

JAR AND FASTENER THEREFOR.

SPECIFICATION forming part of Letters Patent No. 790,750, dated May 23, 1905.

Application filed September 23, 1904. Serial No. 225,632.

To all whom it may concern:

Be it known that we, JOSEPH J. RANNEY and RALPH D. TINKHAM, of Monmouth, in the county of Warren and State of Illinois, have 5 invented certain new and useful Improvements in Jars and Fasteners Therefor, of which the following is a specification.

Our present invention relates to jar-closures, and particularly to that class or type 10 thereof in which a spring is used to exert a first or primary degree of pressure on the lid or cover of the jar, and thereby on the usual gasket or packing-ring, and in which other means are used to exert a secondary or additional pressure thereon and by the use of 15 such means to provide a fastener or closure which will effectually seal the jar and prevent its contents becoming fermented or putrescent.

20 Another object is to provide a jar and closure therefor which while being a two-degree-pressure fastener or closure yet will be strong, durable, economic of manufacture, efficient in use, and capable of being used 25 many times over.

A further object is to provide a two-degree-pressure closure in the use of which the jars after having been filled and sealed may be 30 compactly boxed and shipped as to eliminate danger of breakage, to economize space, and to prevent the working parts from becoming loosened or disturbed, and thus permit air to enter the package and cause deterioration of the contents.

35 Other objects of the invention will herein-after appear.

The novel means employed in carrying out the aforesaid and other objects of our invention, as well as subsidiary objects, is herein-after 40 described and made the subject-matter of the claims hereto appended. The preferred construction of parts and the arrangement thereof are illustrated in the accompanying drawings, in which—

45 Figure 1 is a vertical sectional elevation, partly broken away; Fig. 2, a top plan, and Fig. 3 a plan of the spring and lever.

Similar numerals are employed to indicate 50 corresponding parts wherever such may occur in the several figures of the drawings.

1 represents a jar having an elongated neck 2, and within the neck aforesaid is a circumferential bead 3, an annular groove 4, a vertical wall 5, and a flange 6, having a horizontal seat or shoulder 6^a. The bead 3 is intersected 55 by a vertical mortise or channel 7. The lid consists of a body 8, having a pendent body member 9, a knob 10, having a groove 10^a in its face, said knob located centrally of the body portion 8, a hollowed-out portion 11, surrounding said knob, and an annular peripheral flange 12, having a flat under surface 12^a, corresponding in outline to the outline of the upper face 6^a of the flange 6, a beveled upper edge 12^b, and a member 12^c. 60

13 represents a metallic spring oblong in form and in one of its arms has a longitudinal slot 14, having a transverse enlargement 14^a for a purpose hereinafter described. The ordinary gasket of resilient material is in all 70 cases to be seated on the shoulders 6^a and the lid 8 placed thereupon, with the lower surface 12^a of the flange 12 contacting said gasket and the body member 9 depending into the mouth or throat of the jar. The spring 13 is of such 75 form that when one of its ends is placed within the groove 4 its other or distal end will extend diametrically across the mouth of the jar to the outer edge of the mortise 7, into which it is forcibly directed with its ends resting 80 against the lower face 3^a of the bead 3 and its mid-length portion contacting the knob 10. The spring is then given a partial rotation on its axis in either direction, which operation will bring both its ends beneath the bead 3 85 and resting and held in place by the lower face thereof, thus exerting a primary degree of pressure on the lid, and thereby the gasket.

15 is a lever of the second order and has a longer arm 16 and a shorter arm 17. At the 90 end of the shorter arm are trunnions 18, and on the shorter and longer arms are lugs 19 20, respectively. The spring 13 being in the position shown by dot-lines at Fig. 1 and it being desired to exert a secondary pressure on 95 the lid and gasket, the shorter arm 17 of the lever is introduced downwardly through the enlargement 14^a of the slot 14, (or it may be introduced laterally and directly through said slot,) with the trunnions fulcrumed in a groove 100

or bearing 10^a in the face of the knob 10, as shown best at Fig. 1, the lugs 19 below the spring and the lugs 20 above it. The lever is then drawn longitudinally of the slot 14 with 5 a sliding movement to the farthest position, with the trunnions 18 resting in the groove 10^a. The arm or handle 16 of the lever being then thrown over into the position shown by full lines at same figure, the lugs 19 will force 10 the median portion of the spring upwardly, and thus exert a maximum degree of downward pressure upon the parts whereon it acts. The lugs 20 will prevent the spring and the lever from becoming disengaged from each 15 other when not in use. In this connection it may here be stated that, if preferred, the enlargement 14^a may be dispensed with. It may be further stated that the force exerted to bring the spring to its full-line position will 20 be reactionary and will cause an effective, absolute, and positive hermetic seal to be formed. Whenever it becomes desirable to open the jar for access to its contents, a reversal of the hereinbefore operations is performed.

25 The parts of the fastener are of such dimensions and are so constructed that when they are in their locked positions they lie in a horizontal plane below that of the upper edge of the neck of the jar, and all danger of 30 accidental displacement of the lever thereby unsealing the jar is averted. This feature of having all moving parts in a horizontal plane lower than that of the upper surface of the neck of the jar, thereby permitting the jars 35 to be piled one on top of another and each having a flat surface to rest upon when so piled, is of great utility, as it economizes space in shipping and, furthermore, lessens the danger of breakage.

40 A bail or any other preferred means of carrying the jar may be secured thereto, if desired. The closure is exceedingly simple and effective. The lever is constructed of one piece of metal, as is also the spring, and both 45 are practically unbreakable. Every part being interchangeable, cheapness is attained, and although the pressure exerted is a powerful one the device may, owing to the construction of the lever, be easily manipulated.

50 The advantages of the invention will be apparent and the operation will be understood from the foregoing description, it being particularly noted that various changes may be made in the details of construction without 55 departing materially from the general idea involved.

Without limiting ourselves strictly to the described form of the parts and the details of construction and arrangement shown, we claim 60 as new—

1. A jar-fastener comprising a lever of the second order, trunnions at the end of the shorter arm thereof, lugs in each arm thereof, and a flat, straight metallic spring having

an elongated longitudinal slot through which 65 the short arm of the lever is adapted to pass.

2. A jar-fastener comprising a lever of the second order, trunnions and lugs on the short arm thereof and lugs on the long arm thereof, and a flat metallic spring having a longitudinal slot in one of its arms, said slot having a transverse enlargement, and the short arm of the lever adapted to be passed through said slot.

3. A device of the character described comprising a flat metallic spring having a longitudinal slot in one of its arms, and a lever having a longer and a shorter arm, lugs and trunnions on the shorter arm and lugs on the longer arm, a jar having an elongated neck, 75 said neck having an internal annular groove and having a vertical mortise from the top of the jar to the groove, the ends of the spring adapted to rest against the upper wall of said groove, a lid having a knob located centrally thereof, said knob having a transverse groove in its face, in which groove the trunnions are adapted to be fulcrumed, all of said parts lying in a horizontal plane below that of the upper edge of the jar.

4. In combination, a jar 1 having a neck 2, a lid 8 having a knob 10, a gasket 6^b, a spring 13, the ends of which are adapted to be engaged by a part of the neck of the jar and its mid-length resting on said knob to give a primary degree of pressure thereon, with a lever 15 fulcrumed on the knob and lugs thereon engaged with said spring to raise it at its mid-length to exert a second degree of pressure, substantially as described.

5. The combination in a device of the character described, of a jar having an upwardly-extended neck, and a horizontal gasket-seat therein, and having a bead and a groove also therein, a gasket, a lid or cover adapted to be seated on said gasket, a knob having a transverse groove in its face, located centrally of said cover, said bead having a vertical mortise, a flat spring having a longitudinal slot in one of its arms, one of said arms adapted to be seated in the first aforesaid groove and its other end adapted to be passed down through said mortise and then given a partial revolution to bring both of its ends into engagement with the upper wall of said groove; 105 with a lever having trunnions at the end of its shorter arm adapted to be seated in the groove in the knob, and lugs on the shorter arm adapted to engage and force the spring upwardly at its mid-length.

6. In combination, a jar having a neck, a jar-cover, said neck having an annular interior groove and a bead having a mortise, a metallic spring having its ends adapted to engage said groove, and having a longitudinal slot in 115 one of its arms, and a lever of the second order, one of its arms adapted to pass through said slot and contact the cover, said lever hav-

ing longitudinal sliding movement in said slot, all of said last-named parts lying when in locked position in a horizontal plane not above that of the upper edge of the neck of the jar.

7. The combination of a jar having a cover and having an annular groove and a bead within its neck, said bead having a vertical mortise, of a metallic, flat spring having a longitudinal slot, the ends of said spring adapted to engage said groove, and a lever having a power-arm and a weight-arm, the latter adapted to pass through said slot and to have sliding movement longitudinally of said slot, all of said last-named parts lying, when in locked position, in a horizontal plane not higher than that of the upper edge of the neck of the jar.

8. In a jar-closure, an angular lever of the second order comprising a power-arm and a weight-arm, trunnions projecting laterally from the end of the weight-arm, lugs immediately above the angle of said lever, and other lugs immediately below said angle.

9. A jar-fastener comprising an angular lever of the second order, trunnions at the end of the weight-arm thereof, lugs immediately below the angle thereof, lugs immediately

above said angle, and a flat metallic spring having a longitudinal slot through which an arm of the lever is adapted to pass and have sliding movement lengthwise thereof.

10. The combination of an angular lever of the second order having a power-arm and a weight-arm, trunnions projecting laterally from the end of the weight-arm, lugs immediately above the angle of said lever, lugs immediately below said angle, and a straight metallic spring having an elongated longitudinal slot through which one arm of said lever is adapted to pass and to have sliding movement therein; with a jar having an annular groove and a mortised bead in the neck thereof, a cover, a gasket-seat and a gasket, all of said first-named parts lying, when in secured position, in a horizontal plane not higher than that of the top of the neck of the jar.

In testimony whereof we have hereunto set our hands, this 19th day of September, 1904, in presence of two witnesses.

JOSEPH J. RANNEY.
RALPH D. TINKHAM.
